UNITED STATES PATENT OFFICE.

LOUIS SCHUTTE, OF PHILADELPHIA, PENNSYLVANIA.

INJECTOR.

SPECIFICATION forming part of Letters Patent No. 363,004, dated May 17, 1887.

Application filed January 13, 1887. Serial No. 224,228. (Model.)

To all whom it may concern:

Be it known that I, LOUIS SCHUTTE, of Philadelphia, in the county of Philadelphia and State of Pennsylvania, have invented certain 5 Improvements in Steam-Injectors, of which the following is a specification.

This invention relates to that class of jet apparatus which comprise as the leading elements an actuating-nozzle, a combining-tube in 10 which the actuating-fluid and the fluid to be moved are brought in contact, and a discharge-tube expanding in the direction of the delivery.

The objects of my present invention are, first, to provide the instrument with such inlet and outlet passages and means for attaching pipes thereto in a variety of positions and directions that the attachment of the instrument is greatly facilitated, the use of extra elbows avoided, and space economized; second, 20 to provide improved facilities for the ready adjustment of the instrument to the performance of the particular duties required, and to admit of these adjustments being effected by unskilled labor without the possibility of placing the 25 parts in an inoperative position.

In the accompanying drawing the figure represents a longitudinal central section through a steam-injector having my improvements incorporated therein.

30 Referring to the drawing, A represents the body of the instrument, B the nozzle for the actuating-fluid, C the combining tube or nozzle, and D the discharge-tube. With the exception of the peculiarities hereinafter described, the parts are of ordinary construction and arrangement, the nozzle B being arranged to deliver the actuating-fluid centrally into and through the mixing-tube C, which in turn delivers through the tube D in the direction 40 indicated by the arrow.

In order to adapt the instrument for the convenient application of the discharge-pipe in different positions, as may be required under different circumstances, I provide the body A 45 at one end with the two delivery-openings, E and E', having their axes at right angles to each other, the first passing through the side of the body and the second passing through its end directly opposite the discharge-tube D. 50 The two openings are made of equal diameter

and threaded alike, in order that one or the other may be closed at will by means of a plug, G, provided for the purpose. The discharge-pipe may be screwed into either one of the openings, as circumstances may demand, and 55 the other opening closed by the plug.

In order to permit the application of the steam-supply pipe in different positions, I provide at the receiving end of the apparatus two internally-threaded openings, H and H', one 60 in the end and the other in the side. These openings are of equal diameter and threaded alike, so that the steam-supply pipe may be inserted in the one or the other, as occasion requires. A plug, I, is provided for the purpose of closing one or the other of these openings, as required.

By providing the instrument with the two openings for the receiving-pipe and the two openings for the discharge-pipe, and with the 70 plugs adapted for transposition, as described, I adapt the same for ready attachment in all, or nearly all, positions which will be encountered, at the same time avoiding the employment of the extra elbows and other connections which 75 are frequently demanded by the ordinary construction, and which are for many reasons objectionable.

In order to permit the adjustment of the instrument for the performance of its duties under different conditions, I provide a reversible spindle, J, which may be threaded into the plug I, or into other suitable support. This spindle has its two ends of different diameters, and is provided with a central collar and screw- 80 threads *a* on both sides of the collar, so that it may be turned end for end at will, and screwed into position with one or the other of its ends projecting into the actuating-nozzle B, as occasion may require. By the use of the 85 larger end the steam-passage through the nozzle B is reduced. When a large supply of steam is demanded, the spindle may be entirely removed.

It will be perceived that by means of the removable and reversible spindle three distinct 90 adjustments may be given the instrument as regards the quantity of the steam-supply. It will also be observed that these adjustments may be effected by unskilled persons without 95 100

danger of rendering the instrument inoperative.

Having thus described my invention, what I claim is—

- 5 1. In an injector having a steam-nozzle, a mixing-tube, and a discharge-tube, an external body inclosing and sustaining said parts, said body provided at its discharge end with duplicate threaded delivery-openings at right angles to each other, and with a plug changeable from one to the other of said openings at will.
- 10 2. In an injector containing a steam-nozzle, a mixing-tube, and a discharge-tube, an internal body inclosing and sustaining said parts, said body provided at its end with duplicate openings at right angles to each other, and with a

plug changeable from one to the other of said openings at will.

3. In an injector or jet apparatus having a 20 combining and a discharge tube, a reversible spindle having its two ends of different sizes.

4. The spindle J, having the central collar and the screw-threads, in combination with a plug or support adapted to permit the reversing of the spindle therein. 25

In testimony whereof I have hereunto set my hand, this 3d day of January, 1887, in the presence of two attesting witnesses.

LOUIS SCHUTTE.
